UNITED STATES PATENT OFFICE.

HARRY L. WILSON, OF ERIE, PENNSYLVANIA.

DRY PIPE FOR BOILERS.

SPECIFICATION forming part of Letters Patent No. 618,311, dated January 24, 1899.

Application filed August 27, 1898. Serial No. 889,888. (No model.)

To all whom it may concern:

Be it known that I, HARRY L. WILSON, a citizen of the United States, residing at Erie, in the county of Erie and State of Pennsylvania, have invented certain new and useful Improvements in Dry Pipes for Boilers; and I do hereby declare the following to be a full, clear, and exact description of the invention, such as will enable others skilled in the art to which it appertains to make and use the same.

This invention relates to dry pipes for boilers, the object in view being to provide an attachment for boilers connected with the steam-outlet and arranged on the inside of the boiler so as to prevent the lifting of the water and permitting the steam to be delivered to the steam-outlet in as dry a state as possible.

By means of the invention the steam is taken from a large area at the highest possible point within the boiler.

The detailed objects and advantages of the invention will more fully appear in the course of the subjoined description.

The invention consists in a dry pipe for steam-boilers embodying certain novel features and details of construction and arrangements of parts, as hereinafter fully described, illustrated in the drawings, and incorporated in the claims.

In the accompanying drawings, Figure 1 is a longitudinal section of the boiler, taken also through a combination dry pipe and separator constructed in accordance with this invention. Fig. 2 is a transverse vertical section through the same.

Similar numerals of reference designate corresponding parts in the drawings.

Referring to the drawings, 1 designates an ordinary steam-boiler provided with the usual steam-outlet 2, which for convenience is shown located centrally of the top of the boiler.

In carrying out the present invention I employ a pipe 3, which is made in sectional form, comprising an upper, inner, and smaller section 4 and an outer, lower, and larger section 5. The upper section 4, which forms a separator, or, in other words, a device for separating the steam and water of condensation, is in the form of a channel-bar, comprising an upper horizontal wall or body portion 6, having depending parallel longitudinal

flanges 7 and closed at both ends by means of pendent end flanges 8. At a central point the separator or upper section 4 is provided with an outwardly-extending discharge-neck 9, which is fitted to the steam-outlet 2, so as to conduct the steam thereto. The lower section 5 or bottom portion of the dry pipe is also in the form of a channel-bar, comprising a lower horizontal wall or body portion 10 and upwardly-extending longitudinal parallel flanges 11, which are set at a greater distance apart than the flanges 7, so as to leave an intervening space between the two sets of flanges on the upper and lower sections of pipe, as shown in the cross-sectional view. The ends of the lower section 5 are also closed by outwardly-extending end flanges 12, which are also arranged outside of and at a distance from the flanges 8. The dry pipe as a whole is supported by means of bolts 13, arranged at suitable intervals and passing through the top of the boiler and also through the body portions of the upper and lower sections of the dry pipe. The heads of these bolts are arranged outside of the boiler, while nuts 14 are placed upon the lower ends of the bolts, and by means of these nuts the sections of the dry pipe may be adjusted vertically for varying the distance between the top 6 of the flanges 11 and the inner surface of the boiler. Finally the lower section 5 is provided adjacent to each end with drip-holes 15, which will allow the water of condensation contained in the dry pipe to fall back into the boiler.

The object of the arrangement above described is to provide a tortuous passage for the steam, the latter having to pass first over the upper edges of the flanges 11 and then through horizontal rows of perforations 16, located slightly above the bottom edges of the flanges 7 and 8 of the upper section or separator 4, the steam thus finding its way to the outlet 2. The space between the flanges 11 and the boiler is limited to about twice the area of the steam-pipe, compelling the steam to flow out over the full area of said dry pipe. A further object of the inner channel-bar is to form a tortuous passage for the steam, thus eliminating any retained water in the steam, and this water falls to the bottom of the outer channel and then passes through the drip-holes back into the boiler. In this manner

the water is prevented from being lifted by the steam and allowed to enter directly into the outlet, and the steam is consequently delivered to the outlet in as dry a state as possible. The steam is also taken off from the highest point in the boiler.

Having thus described the invention, what is claimed as new, and desired to be secured by Letters Patent, is—

10. 1. The combination with the outlet of a steam-boiler, of a separator in the form of a channel-bar communicating with the steam-outlet and having depending longitudinal end flanges perforated near their lower edges, a
15. second channel-bar of larger size disposed reversely to the aforesaid channel-bar with its flanges extending outside of the flanges of the first-named channel-bar, and means for supporting and adjusting both channel-bars, substantially as described.

2. The combination with the steam-outlet of a boiler, of a dry pipe in the form of a channel-bar having an upwardly-extending surrounding flange, bolts for adjustably supporting said pipe, and a separator consisting of a second channel-bar disposed reversely to the first-named channel-bar and having a depending surrounding flange which rests on the lower channel-bar and is provided with openings near its bottom edge, the first-named channel-bar being provided at suitable points with drip-openings, and the upper channel-bar having communication with the steam-outlet, substantially as described. 25

In testimony whereof I affix my signature 30 in presence of two witnesses.

HARRY L. WILSON.
